UNITED STATES PATENT OFFICE.

RICHARD CLARANCE SMITH AND MOSES THOMAS SINCLAIR, OF PLYMOUTH, WEST VIRGINIA.

RAILWAY-CROSSING.

1,028,622.

Specification of Letters Patent. Patented June 4, 1912.

Application filed December 9, 1911. Serial No. 664,850.

To all whom it may concern:

Be it known that we, RICHARD CLARANCE SMITH and MOSES THOMAS SINCLAIR, citizens of the United States, residing at 5 Plymouth, in the county of Putnam and State of West Virginia, have invented certain new and useful Improvements in Railway-Crossings, of which the following is a specification, reference being had to the accompanying drawings.

This invention relates to new and useful improvements in railroad crossings, and has for its object to provide a crossing for railroads, adapted to minimize the amount of 15 noise occasioned when a train is passing over the crossing.

Another object of the invention is to provide a pair of similar rails spaced a desired distance apart, and a second pair of similar 20 rails spaced a desired gage apart and adapted to angularly engage the first mentioned pair of rails, so that a train passing over either one of the pairs of rails will not be hampered by the other pair of rails.

Another object of the invention is to provide a crossing of this character which will possess advantages in points of efficiency and durability and is inexpensive of manufacture and at the same time is simple in 30 construction and operation.

With the above and other objects in view the invention consists in the novel features of construction and the combination and arrangement of parts hereinafter described, 35 pointed out in the claim and shown in the accompanying drawings, in which—

Figure 1 is a perspective view of our invention; Fig. 2 is a sectional view on the line 2—2 of Fig. 1, and Fig. 3 is a detail 40 fragmentary perspective view.

Referring more particularly to the drawings 1 indicates the unbroken main rails and 2 indicates the cross rails running at right angles to the main rails. These cross rails 45 are connected by means of the rail sections 3 disposed between the main rails and arranged in alinement with the rails 2.

The main rails 1 and the cross rails 2 are provided with a beveled face 3' on their 50 outer ends which is adapted to abut against the beveled face of the main track rails 2' which will overcome any running or creeping of the track at or near the crossing.

The base flanges 4 of the main rails are 55 provided with the notches 5 adapted to re-

ceive the ends of the base flanges of the inner ends of the cross rails, the tread of said main rails being cut away, at 6, so that the tread of the cross rails will fit snugly against the main rail and the web of the 60 main rails are enlarged at this point, as shown at 7, so that the cross rails will abut tightly up against the main rails.

On the inner side of the main rails and adjacent the inner ends of the cross rails 65 the recesses 8 are formed and adapted to receive the ends of the rail sections 3, the tread of said rail sections being cut away at its ends, as shown at 9, to form the aperture 10, similar apertures 11 being formed in the 70 main rails 1. The main rails 1, the cross rails and the rail sections 3 are securely spiked to the ties 12 by means of the spikes 13. The inner ends of the cross rails and the rail sections are held rigidly in place by 75 means of the rods 14 arranged in alinement with the rail sections 3 and having their ends disposed through the openings 15 in the main rails and then through the eyes 16 formed on the ends of the bolts 17 which 80 are arranged transversely through the web of the inner end of the cross rails. Nuts 18 are threaded on the ends of said rods to hold the rail sections and rails rigidly in place.

It will be seen that by having the rods 14 disposed through the eyes 16 of the bolts 17 and the nuts 18 threaded on said rods, the inner ends of the cross rails can be drawn up tightly and made to fit snugly up 90 against the main rails thus preventing said main rails from spreading and holding the rail sections 3 in a rigid position.

While we have shown and described the preferred form of our invention, it will be 95 obvious that various changes in the details of construction and in the proportions may be resorted to for successfully carrying our invention into practice without sacrificing any of the novel features or departing from 100 the scope thereof.

Having thus described the invention, we claim:

A railway crossing comprising main rails, 105 cross rails having their inner ends abutting against said main rails, said main rails having an enlarged portion formed thereon at the intersection of the cross rails, and recesses formed on the inner side of said main rails adjacent the inner ends of the cross 110 rails

rails, rail sections having their ends disposed in said recesses and arranged in alignment with the cross rails, securing rods arranged in alignment with the rail sections and having their ends disposed transversely through the main rails, bolts arranged transversely in the inner ends of the cross rails, having eyes formed at each end thereof through which the ends of said rods are adapted to pass and nuts threaded on the

ends of said rods to hold said rails rigidly in place.

In testimony whereof we hereunto affix our signatures in the presence of two witnesses.

RICHARD CLARANCE SMITH.
MOSES THOMAS SINCLAIR.
